CLAIM

The ornamental design for a sput cap for cosmetic container, as shown and described.

DESCRIPTION

FIG. 1 is a perspective view of a sput cap for cosmetic container;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof; and,

FIG. 8 is another perspective view thereof.

In the drawings, the broken lines depict portions of a sput cap for cosmetic container that form no part of the claim.

1 Claim, 4 Drawing Sheets(56)
